(57) CLAIM

The ornamental design for a bin, as shown and described.

DESCRIPTION

FIG. 1 is a perspective view of a first embodiment of a bin; FIG. 2 is a left side view of the bin illustrated in FIG. 1; FIG. 3 is a right side view of the bin illustrated in FIG. 1; FIG. 4 is front view of the bin illustrated in FIG. 1; FIG. 5 is a back view of the bin illustrated in FIG. 1; FIG. 6 is a top view of the bin illustrated in FIG. 1; and, FIG. 7 is a bottom view of the bin illustrated in FIG. 1. The broken lines shown in the drawings are included for purposes of illustrating portions of the bin and form no part of the claimed design.

1 Claim, 3 Drawing Sheets
